UNITED STATES PATENT OFFICE.

SEPTIMUS TAYLOR WILLIAMS, OF DYERSBURG, TENNESSEE.

WAGON-BRAKE.

SPECIFICATION forming part of Letters Patent No. 643,437, dated February 13, 1900.

Application filed November 16, 1899. Serial No. 737,207. (No model.)

To all whom it may concern:

Be it known that I, SEPTIMUS TAYLOR WILLIAMS, residing at Dyersburg, in the county of Dyer and State of Tennessee, have made 5 certain new and useful Improvements in Wagon-Brakes, of which the following is a specification.

My invention is an improvement in brakes adapted for farm and other heavy wagons. 10 It is more particularly an improvement in that class of such brakes in which a brake-bar is arranged and adapted to rotate upon its own axis and is connected with a fixed part of the wagon-frame by a rope or chain 15 in such manner that upon rotation of the bar the chain is taken up by winding upon it and the bar thereby brought in contact with the wheels.

My invention relates particularly to means 20 for suspending and guiding the roller brake-bar, as hereinafter described.

In the accompanying drawings, Figure 1 is a perspective view of the rear portion of a wagon-gear provided with my improved brake. 25 Fig. 2 is a section (see line 22, Fig. 1) showing the brake-bar applied to the wheels as required for braking. Fig. 3 is a similar view showing the brake-bar thrown off the wheels. Fig. 4 is a plan view showing the parts in 30 the position illustrated in Fig. 1.

a indicates the reach or coupling-pole, *b* the rear hounds, *c* the rear axle, and *d* the rear wheels, of the wagon-gear.

The roller brake-bar 1 is suspended in front 35 of the wheels *d* by means of curved or arc-shaped loops 2, which are formed of small iron rods curved to the required shape and rigidly connected with the brake-bar. Supports for such loops or guides are provided 40 by means of an iron bar 3, which extends across the reach and hounds at a point just in front of the forward portion of the wheels *d* and whose bent or dropped ends project through the said loops, as shown in Fig. 1. 45 The said bar 3 is held immovable by suitable fastening devices. A chain 4 is attached to the axle *c* and also to the brake-bar 1 in such manner that when the brake-bar is rotated the chain is taken up by being wound thereon, as shown in Fig. 2. A long iron brake-lever 5 is rigidly attached to one end of the

brake-bar 1 and in its normal position extends rearward at an angle of about forty-five degrees. The weight of the lever 5 suffices when in this position to hold the brake-bar 1 55 away from or out of contact with the wheels *d*, as shown in Fig. 3, the ends of the brake-supporting rod 3 being then at the upper ends of the loops 2. The loops thus serve to hold the brake-bar 1 away from the wheels and 60 prevent accidental application of the brake. When the brake-lever 5 is raised to a vertical position, or thereabout, as shown in Fig. 2, the brake-bar 1, being rotated upon its axis, takes up or shortens the chain 4 and is 65 thus drawn backward against the wheels *d*, as shown in Fig. 2, thus effectively braking the same. In this operation the loops 2 ride on the ends of bar 3, and thus guide as well as support the brake-bar in its movement. 70

Thus constructed and adapted to operate my improved brake is simple, durable, effective, and easily operated.

It is obvious that a wire or hempen rope may be substituted for the chain 4. It is also 75 apparent that a rod may be connected with the brake-lever 5, as shown in Fig. 1, and extended forward into suitable position for attachment to a hand-lever (not shown) which may be conveniently operated by the driver. 80

What I claim is—

1. In a wagon-brake of the class specified, the combination, with the reach and wheels, of a rotatable brake-bar, a chain, or equivalent, attached thereto and to the wagon-frame, 85 a lever attached to the brake-bar, for use in rotating it, and adapted, when thrown down, to rotate it in the direction required for rewinding the chain, and rigid devices attached to the brake-bar and coacting with fixed parts 90 on the frame, to automatically throw the brake-bar away from the wheels when the lever is lowered, substantially as shown and described.

2. In a wagon-brake of the class specified, 95 the combination, with the reach and wheels, of a rotatable brake-bar, a chain or equivalent connecting the same with the rear axle, curved or arc-shaped, rigid guide-loops attached to the brake-bar, fixed lateral projections on the frame upon which the said loops are supported and guided, and a brake-lever 100

attached to the bar for rotating it, substantially as shown and described.

3. In a wagon-brake of the class specified, the combination, with the reach, rear wheels, 5 and a bar secured upon the said reach and extending laterally as shown, of the rotatable brake-bar having arc-shaped loops attached thereto and curving upward and rearward

therefrom, for sliding engagement with the ends of the fixed bar, a chain, and an operating-lever arranged and connected with the brake-bar, as shown and described. 10
